UNITED STATES PATENT OFFICE.

ARCHIBALD S. CUBITT, OF RUGBY, ENGLAND, ASSIGNOR TO GENERAL ELECTRIC COMPANY, A CORPORATION OF NEW YORK.

ELECTROMAGNETIC SWITCH.

1,071,886.

Specification of Letters Patent.

Patented Sept. 2, 1913.

Original application filed May 16, 1910, Serial No. 561,682. Divided and this application filed October 21, 1911. Serial No. 656,005.

To all whom it may concern:

Be it known that I, ARCHIBALD S. CUBITT, a subject of the King of Great Britain, residing at Rugby, England, have invented 5 certain new and useful Improvements in Electromagnetic Switches, (division of my prior application, Serial No. 561,682, filed May 16, 1910,) of which the following is a specification.

10 My invention relates to electromagnetic switches or relays for controlling electric circuits and has for its object the provision of an improved device of this character in which a retarding effect is produced upon 15 the contact member so as to cause a definite time interval between operations of the device controlled thereby.

My present application is a division of my previous application Serial No. 561,682. In 20 said previous application I have described and claimed a system of motor control embodying a plurality of electromagnetically controlled switches or contactors arranged for operation in succession to cut out section 25 by section of resistance interposed in the motor circuit on starting. In the said system there is employed a form of relay distinguished by certain features hereinafter pointed out. The present application covers 30 the relay shown and described in the said application, and while this type of relay is adapted for use in the said control system I do not wish to be limited to this particular use, since it will be obvious to those skilled 35 in the art that my invention may be employed in other kinds of electrical apparatus.

In the drawings, Figure 1 is a front elevation of my improved form of relay; Fig. 2 is a sectional view of the same; Fig. 3 is 40 a fragmentary view showing the relay just after the movable member has been raised; and Fig. 4 is a similar view showing the position of the parts of the relay a certain time after the raising of the core.

45 Referring to the drawings, the parts of the relay are shown as mounted upon a backboard 10 of suitable material such as slate. The field frame of the relay is shown at 11 and within this frame is mounted a 50 coil 12 which, when energized, furnishes the magnetic field into which the core of the relay moves. The core of magnetic material is shown at 14 as inclosed in a

brass tube 15 to the top of which is secured a cylinder member 16 of a dash-pot, within 55 which moves a piston 17 secured to a rod 18 extending upwardly from the top of the core 14, as clearly shown. The piston 17 is provided with a valve of any well-known form, such as the ball valve 19, which allows air 60 to escape freely from below the piston to the space above the same but retards the flow of air in the opposite direction. The bottom of the tube 15 is filled by a plug 20 from which a rod 21 extends downwardly. On 65 this rod is carried a contact disk 22 of well-known form. The contact disk is slideable upon the rod 21 and is yieldingly held against the nuts 23 by the spring 24 which at its lower end rests upon a collar 25 se- 70 cured to the rod 21. The hole in the magnet frame and the actuating coil in which the tube 15 moves is lined with the brass tube 27, supported as shown on the removable washer 28 secured to the bottom of the frame 75 11 by the screws 29, this tube 27 having secured to it at its upper end an iron tube 30 arranged as shown. Another iron tube 31, the position of which may be adjusted in the top leg of the field frame 11, projects downwardly toward the tube 30. By adjusting the position of the tube 31 with reference to the tube 30 the air gap between these may 80 be regulated and the magnetic effect of the coil 12 on the core 14 at a certain current 85 may be adjusted. The core 14 may be tapered at its upper end, as shown, and when so constructed will allow the core to be held in its raised position at different points by the same current in the actuating coil. 90 This particular construction of magnetic field structure and core is, however, no part of my invention but is covered in a co-pending application in the name of Eugene R. Carichoff, Serial No. 504,321, filed June 95 25, 1909, and assigned to the same assignee as this application.

The operation of the relay as thus described is as follows: When the coil 12 is energized the core 14 is attracted upward 100 and in rising carries with it the shell 15 owing to the dash-pot connection between the core and said shell. Fig. 3 shows the core in its raised position and the shell in the position in which it is just after the core 105 has pulled up; the contact disk 22 has been.

raised into engagement with its coöperating fixed contacts and the spring 24 beneath the disk has been put under compression. Immediately after the core has moved to its upper position, the shell 15 and the parts carried thereby begin to drop under the retarding effect of the dash-pot, this movement being induced both by gravity and by the expansion of the spring 24. The falling of the shell 15 may continue until the disk 22 drops out of engagement with its coöperating fixed contacts, as shown in Fig. 4, and if the energization of the magnet coil 12 is dependent upon the circuit through these contacts said coil may be deenergized when the shell 15 reaches the position shown in Fig. 4 and the core 14 may drop, thereby returning the relay parts to the position illustrated in Figs. 1 and 2. The valve in the piston of the dash-pot of course allows air to escape freely from below the piston to above it and permits the core to drop freely within the shell when it is released by the deenergization of the magnetizing coil.

It will be seen that I have provided a relay construction which is particularly desirable and efficient. It is entirely inclosed and therefore no dirt or moisture can therefore enter it to interfere with its proper operation. The arrangement is extremely simple and the desired result is obtained in a very reliable manner.

While I have described my invention as embodied in concrete form for purposes of illustration it should be understood that I do not limit my invention thereto, since various modifications thereof will suggest themselves to those skilled in the art without departing from the spirit of my invention.

tion, the scope of which is set forth in the annexed claims.

What I claim as new and desire to secure by Letters Patent of the United States, is,—

1. A relay comprising an electromagnet, a magnetic member and a non-magnetic member movable in the field of the magnet, a dash-pot connection between said members, and switch contacts carried by the non-magnetic member.

2. A relay comprising an electromagnet core of magnetic material movable in the field thereof, a movable shell surrounding said core, a dash-pot connection between said shell and said core, and switch contacts controlled by said shell in its movement.

3. A relay comprising an electromagnet, a core of magnetic material movable in the field thereof, a movable shell in which said core is arranged for movement, a dash-pot connection between said core and said shell whereby the movement of the one with reference to the other is retarded in one direction, and switch contacts controlled by said shell in its movement.

4. A relay comprising an electromagnet, a core of magnetic material movable in the field thereof, a movable shell loosely surrounding said core, a dash-pot cylinder connected to said shell, a piston connected to said core and movable in said cylinder, a valve in said piston, and switch contacts controlled by said shell in its movement.

In witness whereof, I have hereunto set my hand this 10th day of October, 1911.

ARCHIBALD S. CUBITT.
